HEEL-SLOTTING MACHINE

Harley W. Russ, Haverhill, Mass., assignor to
 United Shoe Machinery Corporation, Borough
 of Flemington, N. J., a corporation of New
 Jersey

Application May 11, 1939, Serial No. 273,041

3 Claims. (Cl. 12—49.1)

This invention relates to machines for operating upon heels and is herein illustrated as embodied in a machine for forming heel-cover-receiving slots in the breasts of interlocking heels such as are disclosed in United States Letters Patent No. 2,121,172, granted June 21, 1938, on an application filed in the name of Fred C. Lovejoy.

It is an object of this invention to provide a machine for quickly and effectively forming in the breast of an interlocking heel cover-receiving slots which extend heightwise of and are parallel to corresponding breast edges of the heel.

The various features of the invention will be understood and appreciated from the following detailed description read in connection with the accompanying drawings, in which

Fig. 1 is a plan view, partly broken away, of the illustrative machine;

Fig. 2 is a perspective view, partly broken away, of the machine in the process of slotting a heel;

Fig. 3 shows in perspective the portion of the machine illustrated in Fig. 2 as viewed from below;

Fig. 4 is a section on line IV—IV of Fig. 1;

Fig. 5 shows a portion of the machine as viewed in the direction of the arrow V (Fig. 1); and

Fig. 6 is a perspective view of a heel which has been slotted by the illustrative machine.

The illustrative machine is described with reference to forming in the breasts of interlocking heels 20 (Figs. 1, 2 and 6) cover-receiving slots 22 (Figs. 2 and 6) which are parallel to corresponding breast edges 24 (Fig. 6) of the heels.

The interlocking heel 20 is placed breast down upon a carrier slide 26 (Figs. 1 and 2), one margin of the breast of the heel engaging a ledge or support 28 (Figs. 1, 2 and 4) and an adjacent side of the heel engaging a curved side gage 30. The carrier slide 26 upon which the heel is mounted is then moved along a guideway 32 (Fig. 2) in a direction 34 (Fig. 1) by the operator who simultaneously therewith forces the margin of the breast of the heel against the ledge 28 and the side of the heel against the gage 30 to insure that the slot 22 formed in the breast by a saw 38, which extends through and above the ledge 28, shall be parallel to the adjacent breast edge 24 of the heel.

The various shoe-guiding instrumentalities are mounted upon a platform 40 having at its side a yoke 42 (Fig. 3) into which are threaded trunnion screws 44, 46, respectively. The end portions of the trunnion screws 44, 46 fit respectively in recesses in the opposite ends of a

bar 48 secured by screws 50 to a bracket 52 extending forwardly from a pedestal 54 (Fig. 1). A housing 51 is secured to the pedestal 54 by screws 53. The trunnion screw 46 is held in its adjusted position in the yoke 42 by a lock nut 55. Secured by screws 56 to the platform 40 is a block 58 into which are threaded screws 60 carrying lock nuts 62. The block 58 has pivoted to it a screw 64 which extends through an opening in a bracket 68 of the pedestal 54 and carries a knurled hand nut 70.

In order to vary the distance the saw 38 projects above the ledge 28, in accordance with the desired depth of the cover-receiving slot 22 to be formed in the heel, the platform 40 may be initially raised or lowered into different operative positions about the common axis of the trunnion screws 44, 46. Such adjustment is readily effected by backing the hand nut 70 away from the bracket 68, releasing lock nuts 55 and 62, and then turning the screws 60 the lower ends of which normally engage the bracket 68. After the platform 40 has been properly adjusted the lock nuts 55, 62 are turned to bind the screws 44, 46 to the yoke 42, and the hand nut 70 is turned upon the screw 64 until it is forced against the lower face of the bracket 68.

Mounted upon the pedestal 54 (Fig. 1) and located in the housing 51 is a bearing 72 for a rotary drive shaft 74 to the forward end of which the circular saw 38 is secured by a screw 76. Secured to the platform 40 by screws 78 (Fig. 3) (only one shown) is a block 80 (Figs. 2 and 4) provided with a pair of recesses 82 (Figs. 1 and 4) in which fit studs 84 (Fig. 4) having flanges 86 and eccentric heads 88. The flanges 86 extend slightly above the top of the block 80 and fit in recesses 90 of the ledge 28.

The ledge 28 and the side gage 30 are normally forced downward by a clamp 94 (Figs. 40 and 2) the upper end of which is secured to the housing 51 by a head 96 (Fig. 1) of a screw 93 threaded into the housing, and the lower forward end of which is forced against the side gage 30. The side gage 30 has a beveled face 100 terminating in a curved edge 102 (Fig. 1) which engages the flat heel-engaging face 103 (Fig. 4) of the ledge 28 and is engaged by the side of the heel at its adjacent breast edge. The beveled face 100 of the side gage 30 may be described as forming an obtuse dihedral angle 104 with the heel-engaging face 103 of the ledge 28.

The side gage 30 may be readily replaced by any one of a plurality of side gages 30 having 55

- edges 102 of different curvatures, in accordance with the heightwise curvatures of the sides of the heels to be operated upon. The side gage 30 may be initially adjusted to vary the distance 5 between the edge 102 of the gage and the saw 38 by turning the eccentric studs 94 about their respective axes, after which the studs are secured in their adjusted positions in the block 80 by set screws 106.
- 10 Secured by screws 108 to the platform 40 is another block 110 which, together with the block 80, forms the arcuate guideway 32 along which the slide 26 travels. The slide 26 is normally urged in a counterclockwise direction as viewed 15 in Fig. 1 by a spring 112 one end of which is attached to the slide and the other end of which is attached to an arm 114 secured to the platform 40.
- The slide 26 has a recess or slot 116 which is 20 shaped and arranged to receive the projecting lip 118 (Figs. 2 and 6) of the interlocking heel 20 and is utilized when the left heel-cover-receiving slot 22 on the heel 20 (as viewed in Fig. 5) is being formed. The operator places the 25 heel 20 breast down against the upper face 120 of the carrier slide 26 with the attaching side of its lip 118 in engagement with the vertical surface 122 of the recess 116 and the left breast edge 24 of the heel in engagement with the edge 30 102 of the side gage 30, as illustrated in Fig. 2. The adjacent margin of the breast 36 of the heel is supported by the ledge 28 which, together with the slide 26, orients the breast of the heel properly with respect to the saw 38 as the heel, 35 the breast of which is constantly held against the edge 102 of the side gage by the operator, is moved, together with the slide 26, past the saw 38 to form the left heel-cover-receiving slot 22 (Fig. 6).
- 40 The heel is then removed from the machine and the carrier 26 is moved back to its starting position shown in Fig. 1 by the spring 112. The operator then places the heel breast down upon the face 120 of the slide 26 with the lower face 45 of its lip in engagement with the rear face 124 (Fig. 1) of the slide and with the right breast edge 24 of the heel in engagement with the edge 102 of the side gage 30, as illustrated in dotted lines (Fig. 1). The carrier slide 26 is then moved 50 in a clockwise direction, as viewed in Fig. 1, by the operator, who constantly forces the side of the heel against the edge 102 of the gage 30 and moves the slide 26, together with the heel, past the saw 38 to form the cover-receiving slot 55 22 at the right side of the heel breast (Fig. 6). By providing the slide 26, in combination with the ledge 28 and the side gage 30, the operator can quickly form in the breast of the heel the heel-cover-receiving slots 22 which are parallel to 60 the corresponding breast edges of the heel and extend depthwise in a direction approximately parallel to the heightwise median plane 126 (Fig. 6) of the heel.
- Having described the invention, what I claim 65 as new and desire to secure by Letters Patent of the United States is:
1. A slotting machine having, in combination, a ledge having an approximately flat face, a gage having a beveled face terminating in a curved 70 edge which is arranged above said face of the

ledge and is engaged by the breast edge portion of a side of an interlocking heel the adjacent margin of the breast of which is in engagement with said face of the ledge, a circular saw extending through and above said face of the ledge and positioned adjacent to the curved edge of the gage, a carrier slide having a face constructed and arranged to cooperate with the ledge in supporting the heel and having a recess constructed and arranged to receive a forwardly projecting lip of said heel, and a guideway for controlling movement of the slide in a curved path extending generally lengthwise of said edge of the gage to facilitate transferring the entire heel one of the breast edges of which is in engagement with said edge past the saw to form in the margin of the breast of the heel a cover-receiving slot which is approximately parallel to said one breast edge of the heel and extends from one end of the heel to the other. 20

2. A slotting machine having, in combination, a ledge constructed and arranged to be engaged by a portion of the breast of an interlocking heel adjacent to a breast edge of the heel, a gage having a curved edge arranged above said ledge and constructed and arranged to be engaged by a side of the heel adjacent to said breast edge, a circular saw extending above the ledge and positioned adjacent to but spaced from the gage, a carrier slide having a recess one side of which is constructed and arranged to be engaged by a forwardly projecting lip of the heel and having a face which is constructed and arranged to be engaged by the breast of the heel and to cooperate with said ledge and said edge of the gage to position the heel, and means for guiding the slide in a curved path which extends lengthwise of the curved edge of the gage to transfer the entire heel which is in engagement with said edge of the gage past the saw to form 40 in the breast of the heel a heel-cover-receiving slot approximately parallel to an adjacent breast edge of the heel. 30

3. A slotting machine having, in combination, a ledge having a flat face, a gage having a beveled face forming an obtuse angle with the flat face of said ledge and having a curved edge arranged to be engaged by the breast edge of an interlocking heel the adjacent lateral margin of the breast of which is in engagement with the ledge, a circular saw extending above the flat heel-engaging face of the ledge, a carrier slide having angularly disposed faces constructed and arranged to be engaged by the breast of the interlocking heel and the forwardly projecting lip of the heel respectively, means for guiding the carrier slide in a curved path to facilitate the transferring of the heel which is mounted upon the slide and has said breast edge in engagement with the arcuate edge of the gage past the 60 saw to form in the breast of the heel a cover-receiving slot which is parallel to said breast edge of the heel, eccentric studs for initially adjusting the gage with relation to the saw and the guideway, and means for initially adjusting the ledge, the gage and the guiding means for the carrier slide with relation to the saw to vary the extension of the saw above said face of the ledge. 65
